UNITED STATES PATENT OFFICE

BENJAMIN F. ALINK, OF SPRING VALLEY, MINNESOTA

CRADLE OR BED CONSTRUCTION

Application filed May 31, 1929. Serial No. 367,440.

This invention relates to a cradle or bed construction and aims to provide a combined support and cradle or bed frame so constructed that the cradle or bed frame used with 5 the support will swing downwardly in a true horizontal plane when the frame is forced downwardly by the hand of a person.

A further object of the invention is to provide a swinging support of this character 10 having means for returning the cradle or bed frame to its normal horizontal position after it has been released by the operator.

A still further object of the invention is 15 the provision of means whereby the cradle or bed frame may be readily and easily removed from the support should it be desired to use the same without the movable support.

With the foregoing and other objects in 20 view which will appear as the description proceeds, the invention resides in the combination and arrangement of parts and in the details of construction hereinafter described and claimed, it being understood that changes 25 in the precise embodiment of the invention herein disclosed, may be made within the scope of what is claimed, without departing from the spirit of the invention.

Referring to the drawings:

Figure 1 is a side elevational view of a 20 device constructed in accordance with the invention.

Figure 2 is a longitudinal sectional view therethrough.

Figure 3 is a transverse sectional view 25 through the device.

Figure 4 is a plan view of the support, the cradle or bed having been removed.

Referring to the drawing in detail, the device includes a base embodying bars 5 supported on the feet 6. Secured to each of the bars 5 is a U shaped member 7 having 30 upwardly extending arms 8, the U shaped member being bolted to its supporting bar 5, by means of the bolts 9 which are shown as passing therethrough. The U shaped members 7 are connected by means of the bars 10 which are secured to the U shaped members at points adjacent to the bars 5, as clearly shown by 35 the drawings, so that the bars 5 will be held

in predetermined spaced relation with each other at all times.

The upper ends of the arms 8 of each U-shaped member 7 are connected by the rods 55 11, which rods support the pivoted arms 12 that are formed with openings disposed at points adjacent to the lower ends of the arms 12, there being provided spacing sleeves 13 and 14 mounted on the rods 11 and arranged adjacent to the arms 12, for holding the arms 12 in proper spaced relation with each other. At the lower extremities of the arms 12 are rods 15 which connect the arms 12.

The reference character 16 designates a 60 board which is provided with transversely disposed bores at its ends, which bores accommodate the rods 15 to the end that the arms 12 at each end of the support, are connected. Disposed at the upper ends of each 65 pair of arms 12 is a substantially long transversely disposed supporting rod 18, the ends thereof being reduced as at 19 to fit within the notches 20 formed in the bars 21 that are secured to the inner surfaces of the side bars 70 22 of the cradle or bed frame mounted on the support, so that the cradle or bed frame may be readily removed or replaced at will.

Secured to the board 16 adjacent to one end thereof, is a plate 23 that has an upstanding 80 end portion 24 formed with an opening to receive one end of the hook 25 that is carried at one end of the coiled spring 26, the opposite end of the coiled spring being secured to the clip 26', which in turn is positioned on the rod 11 at one end of the cradle or bed support, so that as the cradle or bed is forced 85 downwardly, the spring will be placed under tension to return the cradle or bed to its normal horizontal position.

The cradle or bed also includes pairs of vertical rungs or slats that extend upwardly from the side bars 22, the upper ends thereof being connected by the upper rails 23' of the bed or cradle. Connecting the side rails 23' is a rod 24' that extends over the bed or cradle in such a way that an infant lying on the bed may grip the rod 24' and raise himself from his position on the bed, exercising the arms and body.

The springs which are indicated by the ref-

erence character 25' rest on the bars 21, the mattress which is indicated by the reference character 26', being supported on the springs in the usual and well known manner.

5 I claim:

6 A cradle including a base, pairs of upstanding arms mounted on the base and disposed adjacent to the ends of the base, rods connecting the arms, pairs of arms pivotally mounted on the supporting rods, the upper ends of the latter arms being disposed laterally of the supporting rods, the lower ends of the arms extending below the rods, a board connected with the lower ends of the pivoted arms, and adapted to cause the pairs of pivoted arms to move simultaneously, a spring member connected to the board at one end of the board, the opposite end of the spring member having connection with one of the rods to normally hold the pivoted arms in upright positions, and a cradle body pivotally mounted at the upper ends of the pivoted arms.

10 15 20 25 In testimony that I claim the foregoing as my own, I have hereto affixed my signature.

BENJAMIN F. ALINK.
